(57) **CLAIM**

The ornamental design for an automatic soap dispenser, as shown and described.

DESCRIPTION

FIG. 1 is a front, left and bottom perspective view of an automatic soap dispenser showing my new design;

FIG. 2 is a rear, right and top perspective view thereof;

FIG. 3 is a front view thereof;

FIG. 4 is a rearview thereof;

FIG. 5 is a left view thereof;

FIG. 6 is a right view thereof;

FIG. 7 is a top view thereof;

FIG. 8 is a bottom view thereof;

FIG. 9 is a perspective view thereof, showing the foldable part in a closed position; and,

FIG. 10 is a perspective view thereof, showing in an exploded position.

The broken lines shown in the figures are for the purpose of illustrating portions of the automatic soap dispenser, which form no parts of the claimed design.

1 Claim, 10 Drawing Sheets
